US00D335306S

United States Patent [19]
Poisson et al.

[11] **Patent Number:** Des. 335,306
[45] **Date of Patent:** ** May 4, 1993

[54] **WRITING INSTRUMENT**

[75] Inventors: **Norman D. Poisson**, Andover, Mass.;
Walter B. Herbst, Evanston, Ill.;
Paul D. Hurley, Huntington Woods,
 Mich.

[73] Assignee: **The Gillette Company**, Boston, Mass.

[*] Notice: The portion of the term of this patent
 subsequent to Mar. 10, 2009 has been
 disclaimed.

[**] Term: **14 Years**

[21] Appl. No.: **648,431**

[22] Filed: **Jan. 25, 1991**

[52] U.S. Cl. **D19/48; D19/49;**
D19/51; D19/56

[58] Field of Search **D19/35, 36, 41-51,**
D19/54-58, 81-85; 401/6, 99, 100, 103, 88

[57] **CLAIM**

The ornamental design for a writing instrument, as shown and described.

DESCRIPTION

FIG. 1 is a front elevational view of a writing instrument, showing our new design;

FIG. 2 is a left side elevational view, the right side being a mirror image thereof;

FIG. 3 is a rear elevational view;

FIG. 4 is a top plan view; and,

FIG. 5 is a bottom plan view thereof.

The pattern on the barrel of the writing instrument is continuous throughout the area indicated.
